ELECTROMAGNETIC FRICTION APPARATUS

Harry W. Phair, Lyndhurst, N. J., assignor to Empire Electric Brake Corporation, a corporation of Delaware

Application May 22, 1940, Serial No. 336,603

12 Claims. (Cl. 188—138)

This invention relates to electromagnetic friction apparatus, and is concerned more particularly with the provision of improved apparatus for deriving force by friction magnetically induced between an electromagnet and an armature moving relatively thereto.

Apparatus of the character described comprises an electromagnet mounted in light-pressure contact with an armature which is arranged to be moved relatively to the electromagnet. When the electromagnet is energized it is attracted to the relatively moving armature, and in consequence of the friction between the two parts so attracted, a force is imposed on the magnet tending to move it in the direction of movement of the armature. The force thus imposed on the electromagnet may be derived for useful work through any suitable mechanism, such as a lever on which the electromagnet is mounted.

In such apparatus, using an armature composed of ordinary magnetic material, such, for example, as ordinary iron or steel, the force derived at any given degree of energization of the electromagnet varies inversely, and to a considerable extent, with the speed at which the armature moves relatively to the electromagnet. Such variations in the derived force at various relative speeds of the armature to the electromagnet is decidedly objectionable. For example, if the apparatus is employed as a brake operating mechanism in an electromagnetic brake, in which the armature rotates with the wheel of the vehicle or other moving part to be braked, the braking effort which the apparatus is able to produce varies inversely and to a considerable extent with the speed of the wheel or other moving part. At high speeds, therefore, the braking effort for a given degree of magnet energization is much lower than at low speeds.

I have discovered that this objectionable characteristic of electromagnetic apparatus of the character referred to above is due to eddy currents induced in the armature as it moves relatively to the electromagnet when the latter is energized. These eddy currents create a magnetic flux in the armature which opposes the flux produced by the electromagnet. The more rapidly the armature moves relatively to the electromagnet, the stronger are the eddy currents produced therein, and the greater is the opposition of the flux produced by the eddy currents to the flux produced by the electromagnet. Consequently, the higher the speed of the armature relatively to the electromagnet, the less is the magnetic attraction between the electromagnet

and the armature for any given degree of electromagnet energization.

I have further found that if the armature moving relatively to the electromagnet is composed of a magnetic material such as iron containing a substantial proportion of a material such as silicon which inhibits the occurrence of eddy currents, it is possible to derive a substantially constant force from the apparatus, at any given degree of electromagnet energization, over a considerable range of speed of the armature relatively to the electromagnet. It is understood, of course, that in stating that the derived force may be made "substantially constant" over a considerable range of speed, I do not mean the derived force will be absolutely constant. On the contrary, some variation in the derived force will inevitably occur with variations in speed. The expression "substantially constant" as used herein and in the appended claims is intended to mean that, in any given apparatus, the derived force is sufficiently constant so that such force variations as do occur at different speeds of the armature relatively to the electromagnet are within the tolerable range of force variations for that particular apparatus.

Based on the foregoing discoveries, my invention contemplates the improvement, in electromagnetic apparatus of the character referred to above, which comprises employing as the armature a metallic member composed largely of iron and containing silicon in sufficient amount so that the force derived at a given degree of energization of the electromagnet is substantially constant over a considerable range of speed of the armature relatively to the electromagnet. In general a substantial amount up to about 10% by weight of silicon is employed in the armature to obtain the desired results. Armatures composed of an alloy of silicon with iron containing about 3% to about 8% by weight of the silicon have been employed with considerable success.

Apparatus according to the invention generally comprises an armature, which advantageously is a relatively thin, generally disc-shaped member mounted for rotation about its axis, an electromagnet mounted with its pole pieces normally in light-pressure contact with the armature, means for controllably energizing the electromagnet with an electric current, and means for moving the armature relatively to the electromagnet, the armature being composed largely of iron and containing silicon in sufficient amount so that the force derived at a given degree of energiza-

tion of the electromagnet is substantially constant over a considerable range of speed of the armature relatively to the electromagnet.

The armature may be composed wholly of an iron alloy containing silicon in a substantial amount up to about 10% by weight, advantageously from about 3% to 8% by weight, or it may be a composite structure having a surface portion composed of a relatively hard, wear-resistant metallic composition (such as a case-hardened ferrous composition) adapted to engage with the electromagnet, and an underlying portion composed largely of iron and containing a suitable amount, as indicated above, of silicon.

Electromagnetic apparatus of the character described above is well adapted for use as the operating mechanism of a brake, and accordingly a specific embodiment of the invention as applied to an electromagnetic brake is described below in conjunction with the accompanying drawing, in which—

Fig. 1 is a plan of an electromagnetically operated brake embodying the invention;

Fig. 2 is a cross section of the brake shown in Fig. 1, taken substantially along the line 2—2 of Fig. 1;

Fig. 3 is a plan view on a reduced scale showing the mechanical structure of an armature plate of the type employed in the brake shown in Figs. 1 and 2; and

Fig. 4 is a fragmentary cross section through a modified form of armature plate.

The brake shown in the drawing comprises a backing plate 10 on which are mounted a pair of anchors 11. Brake shoes 12 carrying a suitable brake lining 13 are mounted on and carried by the anchors 11. The brake shoes 12 are connected together at their lower ends, approximately diametrically opposite from the anchors, by suitable adjusting means 14 and a spring 15. The brake shoes are provided with the usual hold-down means 16, for holding them against the backing plate, and the usual eccentric adjustment 17, and the eccentric adjustment spring 18.

Mounted on the backing plate 10 is a pivot pin 19 on which a lever 20 is pivotally mounted. The lever 20 is provided with a bifurcated short arm 21 and a long arm 22. The bifurcated short arm 21 carries a brake-actuating pin 23 on which is mounted a roller bearing 24 engaging with the ends of the brake shoes 12 between the anchors 11.

The long arm 22 of the lever carries an annular electromagnet 25 having an inner pole piece 26 and an outer pole piece 27. A suitable annular electromagnet coil is located within the electromagnet, and wires 25a through which electrical energy is supplied to the electromagnet coil run from the magnet up the lever 20 and are taken out through the backing plate 10 at a suitable point. The wires 25a are connected to a battery B or other suitable source of current in series with a rheostat R or other suitable means for controlling the value of the current supplied to the electromagnet.

A brake drum 28 is arranged for rotation with the wheel of the vehicle or other moving part to be braked, and is positioned with its drum surface concentric with and close to the lining 13 of the brake shoes 12. An armature plate 29 in the form of a relatively thin, annular member is mounted in the brake drum 28 against bosses 30 by means of bolts 31 engaging in threaded holes 32 formed in the arma-

ture plate. The hub of the rotating part to be braked, on which the brake drum 28 is mounted, may be secured in any suitable manner to the brake drum, (for example, by bolts extending through holes 28a in the web of the brake drum) and the shaft on which such part is mounted may extend through the central opening 33 of the brake drum, through the corresponding central opening 34 of the armature plate, and, if necessary, through an aligned opening 10a in the backing plate.

The electromagnet 25 mounted on the long arm 22 of the lever is normally held in light-pressure contact with the armature 29 by means of a spring 35. The mounting means for the magnet enabling this light-pressure contact to be maintained, even though the armature plate may wobble slightly or otherwise run out of true, comprises a sleeve 36 closed at one end and securely mounted on the long arm of the lever 22, and a magnet mounting pin 37 slidably mounted within the sleeve 36. The magnet mounting pin extends into the central pole or core of the magnet to a point closely adjacent the working face thereof. The spring 35 is mounted to press at one end against the closed end of the sleeve 36, and against the magnet mounting pin 37 at the other end, so as to press the magnet supported by the pin lightly against the armature plate 29.

The apparatus described above operates as follows: With the backing plate and brake shoes carried thereby held stationary on some rigid support (such as a frame member of a vehicle) and with the rotating brake drum and armature rotating so that the armature moves relatively to the electromagnet, the brake shoes are normally held out of engagement with the brake drum by means of a retracting spring 38. Upon energizing the electromagnet by operating the rheostat R to pass a current of suitable controlled value through the electromagnet coil, the magnet is attracted to the rotating armature with a force that is roughly proportional to the amount of current supplied to the electromagnet. This attraction between the electromagnet and the rotating armature increases the friction between these two parts, and this frictional coupling tends to pull the electromagnet around with the armature. The force thus imposed on the electromagnet is transmitted through the lever 20 and is applied by the short arm of the lever to the end of one of the shoes 12, depending upon the direction of rotation of the armature, and the shoe so acted upon is thereby expanded outwardly into braking engagement with the drum 28. By controllably varying the degree to which the electromagnet is energized, that is, by controllably varying the amount of current supplied to the electromagnet coil, the friction between the rotating armature and the electromagnet is correspondingly controllably varied. In this manner the force applied to the ends of the brake shoes, and the braking effort exerted by the latter, are easily controlled.

If the armature plate is composed of an ordinary magnetic material, such as an ordinary iron or steel, the force with which the brake shoe is expanded at any given degree of energization of the electromagnet (i. e. at any given current value supplied to the electromagnet coil) varies inversely with the speed at which the armature plate 29 is rotating relatively to the electromagnet. If, however, the armature plate

is composed largely of iron containing a substantial amount up to about 10% by weight of silicon, the force derived from the electromagnet as a result of its frictional engagement with the armature plate and applied to the brake shoes is substantially constant over wide ranges of speeds of the armature relatively to the electromagnet.

As pointed out above, these different behaviors of armatures of different compositions appear to be due to the fact that eddy currents are generated in the armature plate during rotation thereof in contact with the electromagnet. If an ordinary iron or steel armature plate is employed, these eddy currents attain a considerable magnitude and are able to develop in the armature a magnetic flux of substantial value which opposes the flux produced by the electromagnet itself. If, however, the armature plate is composed of an alloy of iron and a substance such as silicon capable of inhibiting the occurrence of eddy currents, the magnitude of the eddy currents set up in the armature, is significantly reduced and the attraction of the electromagnet to the rotating armature plate is substantially unopposed, in consequence of which a substantially constant force is derived over a considerable range of speeds of the armature plate relatively to the electromagnet for any given degree of energization of the electromagnet.

The extent to which the force derived from the electromagnet is reduced by an increase in the speed of rotation of the armature, when the latter is composed of an ordinary iron or steel, and the improved results obtained by using an armature according to the invention composed of an alloy of silicon and iron, are shown in the following table. The same electromagnet, energized in each case with a current of the same value in amperes, was employed in conjunction with armature plates of the several different compositions shown. The figures in the body of the table give the force in pounds derived at the electromagnet.

Armature composition	Speed of armature—revolution per minute						
	100	300	400	500	600	700	800
High carbon abrasion-resistant steel	69	50	50	45	40	33	27
Copper steel	53	51	47	44	42	38	36
S. A. E. 4030 steel	68	60	55	51	48	45	38
Silicon steel							
4% silicon	70	68	66	63	59	57	55
5% silicon	63	61	59	58	57	56	55

It will be noted from the foregoing table that in the case of the first three armatures listed the force derived at 800 R. P. M. was about 30% to 60% below the force derived at 100 R. P. M., whereas in the case of the silicon steel armatures the force derived at 800 R. P. M. (700 R. P. M. in the case of the 4% silicon steel) was only about 13% to 19% below the force derived at 100 R. P. M. For practical purposes the force derived using the armatures of silicon steel thus can be considered substantially constant over the range of armature speeds given. It is to be remembered that in this specification and in the claims, in referring to the force derived from the electromagnet as "substantially constant" over a considerable range of speed of armature relatively to electromagnet, variations in the force of the order of 15% occurring over a variation in speed of the order of 800%,

which are tolerable force variations in most practical apparatus, are not beyond the scope of the expression "substantially constant".

The amount of silicon with which the iron of the armature plate is alloyed should be substantial in order to obtain satisfactory results. Ordinarily at least about 3% silicon should be employed, and larger amounts may be used with advantage. In general no particular advantage is obtained using more than about 10% by weight of silicon, and for most practical purposes an upper weight of about 8% by weight is adequate. For many purposes an armature plate composed of about 5% by weight of silicon, and the balance substantially all iron, is economical and quite satisfactory.

The armature plate may be composed wholly of the iron-silicon alloy described above, but advantageous results may be obtained by employing an armature plate having a surface portion 39 (Fig. 4) composed of a relatively hard, wear-resistant metal and an underlying portion 40 composed substantially of an iron-silicon alloy as described above. The hard wear-resistant surface portion 39 of the armature is suitably configured for engagement with the working faces of the pole pieces of the electromagnet. Being hard and wear-resistant, this surface portion of the armature plate will stand up well over long periods of time in operating engagement with the electromagnet working face, and will protect the underlying main body portion 40 of the armature plate, which is composed of the less wear-resistant silicon-iron alloy, from injury due to mechanical causes. The hard wear-resistant surface portion 39 of the armature plate should be relatively thin, so as to interfere as little as possible with the magnetic quality of the armature plate as a whole, and yet should be thick enough so as to protect the underlying portion of the armature. A wear-resistant surface portion of the order of 0.020 inch in thickness generally is amply thick. The main body portion 40 of the armature is of substantial thickness, the actual dimension being dependent upon the particular design of the electromagnet with which it is intended to operate.

Composite armature plates of the character described may be prepared by welding a thin sheet of a case-hardenable steel to a relatively thick sheet of a suitable silicon-iron alloy. The two sheets should, of course, be securely bonded together both for mechanical strength and to eliminate the occurrence of undesirable air gaps in the magnetic circuit.

An advantageous feature of armature plates composed of silicon steel is their ability to resist abrasion, scoring, chipping, and other detrimental effects resulting from heavy rubbing pressure in contact with the electromagnet when the latter is energized. Many steels, when subjected to the service imposed on armature plates in apparatus of the character described above, are badly scored or chipped after a short period of time. Scoring or chipping adversely affects proper functioning of the armature plate to a serious extent. Silicon steel has been found to resist scoring, chipping, and other objectionable types of defacing, and for this reason also may be used with advantage in the armature plate of electromagnetic apparatus of the character described. Ordinary silicon steel such as that described above possesses adequate resistance to abrasion, scoring, chipping, and the like for many purposes, but this resistance may be enhanced by constructing the armature plate, as described

above in conjunction with Fig. 4, with a wear-resistant facing of a case-hardenable ferrous composition.

Resistance of the armature plate of the invention to deformation is aided by the fact that it is composed preferably of a single, relatively thick sheet (ordinarily about one-quarter inch or more in thickness). So far as I am aware, armature plates according to the invention constitute the first use that has been made of such thick sheets of silicon steel. Silicon steels have heretofore been used chiefly in the form of very thin sheets in laminated cores for electrical apparatus, particularly radio transformers.

Although particular reference has been made above to silicon steel for use in armature plates according to the invention, it is understood that the term "silicon steel" as used herein is intended to include other equivalent magnetic metals or alloys in which the development of eddy currents is inhibited and which otherwise possess the advantageous characteristics of silicon steel itself.

Although the invention has been described above with particular reference to the embodiment of electromagnetic apparatus in accordance with the invention in an internal shoe brake, it is understood that the invention is equally applicable to other types of electromagnetically operated brakes, such as external brakes and disc brakes, and to other types of equipment, such as clutches, in which the electromagnetic apparatus may be employed as the operating or control mechanism.

I claim:

1. Apparatus for deriving force by magnetically induced friction comprising an electromagnet, means for energizing the electromagnet, and an armature mounted for movement relatively to the electromagnet and so arranged that upon energization of the electromagnet during movement of the armature relatively thereto a frictional force is produced between the armature and the electromagnet, said armature comprising a metallic member composed largely of iron and containing silicon in sufficient amount so that the force derived at a given degree of energization of the electromagnet is substantially constant over a considerable range of speed of the armature relatively to the electromagnet.

2. Apparatus for deriving force by magnetically induced friction comprising an electromagnet, means for energizing the electromagnet, and an armature mounted for movement relatively to the electromagnet and so arranged that upon energization of the electromagnet during movement of the armature relatively thereto a frictional force is produced between the armature and the electromagnet, said armature comprising a metallic member composed largely of iron and containing a substantial amount up to about 10% by weight of silicon, the amount of silicon present in the armature being sufficient so that the force derived at a given degree of energization of the electromagnet is substantially constant over a considerable range of speed of the armature relatively to the electromagnet.

3. Apparatus of the character described comprising an electromagnet, means for energizing the electromagnet, and an armature mounted for relative movement in magnetic relation and frictional engagement with said electromagnet, said armature being composed largely of iron and containing silicon in sufficient amount so that the force derived at a given degree of ener-

gization of the electromagnet is substantially constant over a considerable range of speed of the armature relatively to the electromagnet.

4. Apparatus of the character described comprising an electromagnet, means for energizing the electromagnet, and a generally disc-shaped armature mounted for rotation relatively to the electromagnet in magnetic relation and frictional engagement therewith, said armature being composed largely of iron and containing a substantial amount up to about 10% by weight of silicon, the amount of silicon present in the armature being sufficient so that the force derived at a given degree of energization of the electromagnet is substantially constant over a considerable range of speed of the armature relatively to the electromagnet.

5. Apparatus of the character described comprising an armature, an electromagnet mounted with its pole pieces normally in light-pressure contact with the armature, means for controllably energizing the electromagnet to produce relatively heavy-pressure contact between said armature and electromagnet, and means for moving the armature relatively to the electromagnet, said armature being composed largely of iron and containing silicon in sufficient amount so that the force derived at a given degree of energization of the electromagnet is substantially constant over a considerable range of speed of the armature relatively to the electromagnet.

6. Apparatus of the character described comprising a generally disc-shaped armature mounted for rotation about its axis, an electromagnet mounted with its pole pieces normally in light-pressure contact with the armature, and means for controllably energizing the electromagnet to produce relatively heavy-pressure contact between said armature and electromagnet, said armature being composed largely of iron and containing from about 3% to about 8% by weight of silicon.

7. Apparatus of the character described comprising an armature, an electromagnet mounted with its pole pieces normally in light-pressure contact with the armature, means for controllably energizing the electromagnet to produce relatively heavy-pressure contact between said armature and electromagnet, and means for moving the armature relatively to the electromagnet, said armature having a surface portion in contact with the electromagnet composed of a relatively hard, wear-resistant metallic composition and an underlying portion composed largely of iron containing silicon in sufficient amount so that the force derived at a given degree of energization of the electromagnet is substantially constant over a considerable range of speed of the armature relatively to the electromagnet.

8. Apparatus of the character described comprising a generally disc-shaped armature mounted for rotation about its axis, an electromagnet mounted with its pole pieces normally in light-pressure contact with the armature, and means for controllably energizing the electromagnet to produce relatively heavy-pressure contact between said armature and electromagnet, said armature having a surface portion in contact with the electromagnet composed of a relatively hard, wear-resistant ferrous composition securely bonded to an underlying portion composed largely of iron containing from about 3% to about 8% by weight of silicon.

9. An electromagnetic brake comprising a backing plate, an electromagnet supported from said backing plate, a rotatable brake drum, an armature mounted for rotation with said drum in light-pressure contact with the pole pieces of said electromagnet, means for controllably energizing the electromagnet, and brake shoes arranged to be actuated by said electromagnet upon energization thereof during rotation of the armature, said armature being composed largely of iron and containing silicon in sufficient amount so that the force with which the brake shoes are actuated at a given degree of energization of the electromagnet is substantially constant over a considerable range of speed of the armature relatively to the electromagnet.

10. An electromagnetic brake comprising a backing plate, an electromagnet supported from said backing plate, a rotatable brake drum, an armature mounted for rotation with said drum in light-pressure contact with the pole pieces of said electromagnet, means for energizing the electromagnet, and brake shoes arranged to be actuated by said electromagnet upon energization thereof during rotation of the armature, said armature having a surface portion in contact with the electromagnet composed of a relatively hard, wear-resistant ferrous composition securely bonded to an underlying portion composed largely of iron containing silicon in sufficient amount

so that the force with which the brake shoes are actuated at a given degree of energization of the electromagnet is substantially constant over a considerable range of speed of the armature relatively to the electromagnet.

11. An armature plate adapted for use in apparatus of the character described comprising a generally disc-shaped metallic member having a surface adapted to engage with an electromagnet, the metal at and adjacent said surface being of a relatively hard, wear-resistant metallic composition, and the metal underlying said hard, wear-resistant surface portion being composed largely of iron and containing silicon in sufficient amount so that the force derived at a given degree of energization of the electromagnet is substantially constant over a considerable range of speed of the armature relatively to the electromagnet.

12. An armature plate adapted for use in apparatus of the character described comprising a relatively thin, generally disc-shaped member having a surface portion composed of a relatively hard, wear-resistant ferrous composition adapted to engage with the pole pieces of an electromagnet, said surface portion being securely bonded to an underlying portion composed largely of iron and containing from about 3% to about 8% by weight of silicon.
